UNITED STATES PATENT OFFICE.

FRANK HAYNES, OF LIMON, COLORADO.

BILLIARD-CUE TIP.

1,153,491.

Specification of Letters Patent. Patented Sept. 14, 1915.

Application filed October 16, 1913, Serial No. 795,601. Renewed August 10, 1915. Serial No. 44,830.

To all whom it may concern:

Be it known that I, FRANK HAYNES, a citizen of the United States, residing at Limon, in the county of Lincoln and State of Colorado, have invented certain new and useful Improvements in Billiard-Cue Tips, of which the following is a specification, reference being had therein to the accompanying drawing.

10 This invention relates to a cue tip which is adapted to be used in combination with billiard or pool cues, and has for its object the production of a tip which may be easily removed when desired.

15 Another object of this invention is the production of a ferrule which is adapted to be fitted upon the end of a cue for holding the tip in firm engagement with the outer end of the cue.

20 With these and other objects in view, this invention consists in certain constructions and arrangements of parts as will be fully brought out in the following specification and claims.

25 In the accompanying drawings, Figure 1 is a side elevation of a portion of a cue, showing my device carried thereby. Fig. 2 is a longitudinal section of a portion of a cue showing the tip and ferrule carried 30 thereby. Fig. 3 is a section taken on the line 3—3 of Fig. 2, looking in the direction of the arrows. Fig. 4 is a detail perspective view of the forward end of a cue. Fig. 5 is a perspective view of the metallic ferrule. Fig. 6 is a detail perspective view of the tip.

35 Referring to the accompanying drawings by numerals, 1 indicates the cue having a reduced forward end 2. This reduced forward end 2 is provided with rounded sides 3 and flat sides 4. A pair of longitudinally-extending grooves 5 are formed in this reduced portion 2 so as to communicate with the flat sides 4. These grooves 5 are formed 45 so as to be positioned opposite each other and extend for a distance back into the cue 1, thereby forming pockets 6. It will be noted that by reducing the forward end of the cue, as illustrated at 2, there will be formed a 50 shoulder 7 at the inner end of the reduced portion 2. The metallic ferrule which is carried by this reduced portion 2 comprises a sleeve 8 which is so formed as to fit snugly upon the reduced portion 2 of the cue 1. 55 By forming this ferrule in this manner, it will be seen that the same will be provided

with flat sides 9 and rounded sides 10 for conforming to the contour of the shape of the reduced portion 2 of the cue 1, thereby firmly holding the ferrule in its correct 60 position.

In order to provide a tip for the cue which may be easily removed when the same becomes worn or for any other reason, the device is provided with a detachable tip 11. 65 This tip 11 comprises a flat rounded body in which there are formed the sockets 12 and a communicating opening 13, this opening 13 communicating with the sockets 12. Parallel spring arms 14 are carried by this tip 70 11 and are integrally connected by the bridge 15, thereby forming a substantially U-shaped structure. When the tip 11 is placed in position upon the outer end of the cue, the parallel spring arms 14 are passed through the 75 grooves 5 until the tip 11 rests snugly upon the outer end of the reduced portion 2. Since the ferrule 8 incloses the grooves 5, the outer ends of the arms 14 may be bent outwardly to form retaining lips 16. These 80 lips 16 rest within the pockets 6 and bear upon the inner end of the ferrule 8, as clearly disclosed in Fig. 2, whereby the tip will be held in firm engagement with the outer end of the reduced portion 2 of the cue. It is obvious that when the tip 11 becomes worn, by bending the lips inwardly 85 the tip may be easily removed from the outer end of the reduced portion 2 by drawing the arms 14 from the grooves 5. 90

From the foregoing description, it will be seen that a simple tip has been produced for billiard or pool cues which is firmly held in engagement with the outer end of a cue and which may be easily removed when desired. 95

By carefully referring to the drawing, it will be seen that the lips 16 terminate evenly with the outer face of the ferrule 8, while the inner ends of the arms 14 are positioned within the sockets 12 of the tip 11 whereby an even wearing surface has been produced throughout the entire length of the cue, ferrule and tip. 100

What is claimed as new is:—

1. A billiard or pool cue comprising a body, said body provided at its forward end with a reduced portion, said reduced portion provided with oppositely-disposed longitudinally-extending grooves extending backward into said body thereby forming pockets, said reduced portion provided with a plurality of rounded sides and a plurality 105 110

of flat sides, a metallic ferrule conforming in shape to the contour of said reduced portion, said ferrule fitting snugly upon said reduced portion whereby said ferrule will 5 be held in its correct position, and a tip positioned upon the outer end of said reduced portion, said tip provided with parallel spring arms, said arms extending into said grooves and engaging said ferrule for de- 10 tachably holding said tip in engagement with the outer end of said reduced portion.

2. A billiard or pool cue comprising a body, a reduced portion formed upon the outer end of said body, said reduced portion 15 provided with longitudinally-extending oppositely-disposed grooves, said body also provided with pockets communicating with said grooves and with a shoulder adjacent said reduced portion, a ferrule carried by 20 said reduced portion and engaging said shoulder of said body, a tip positioned upon

the outer end of said reduced portion, said tip provided with sockets and with an opening communicating with said sockets, parallel spring arms positioned within said sockets, a bridge integrally connecting said spring arms, said arms normally positioned within the grooves formed in said reduced portion, said parallel arms terminating in outwardly-bent lips adapted to engage the 25 inner end of said ferrule whereby said tip will be held firmly upon the outer end of said reduced portion, and said lips terminating evenly with the outer surface of said ferrule, thereby forming an even wearing 30 surface.

In testimony whereof I hereunto affix my signature in presence of two witnesses.

F.RANK HAYNES.
